LEER LOADER

Louis Beon, Salem, N. J., assignor to Salem Glass Works, Salem, N. J.

Application November 25, 1932, Serial No. 644,236

9 Claims. (Cl. 198—31)

The present invention relates to loaders or feeders for leers.

An object of the invention is to provide an efficient loading mechanism for cooperation with a leer for annealing glassware, and particularly for cooperation with leers of the type in which a leer conveyor carries the ware through the leer for the annealing operation.

A further object of the invention is the provision of a leer loader capable of transferring, for example from a bringing-up or delivery conveyor, glassware, for example bottles, jars, etc., of different sizes and particularly of different heights, the loader for this purpose being so constructed that the loading member may have a rectilinear, or substantially rectilinear, infeed motion for pushing the ware onto the leer conveyor, such motion allowing the loader to be used with ware of very small height and with smoothness and steadiness and reliability so that the ware is transferred to the leer conveyor in desired position thereon.

Another object of the invention is the provision of a loader having a loading member or pusher operable through a cycle, and called into operation by the arrival of an article to be annealed in a predetermined position with respect to the leer conveyor.

Another object is the provision of a loader so constructed that the progress of fresh ware, for example, carried by the bringing-up conveyor, is not delayed during the infeeding operation, but the bringing-up conveyor may be constantly in motion.

Another object is to provide such a loader which operates through a cycle, including a ware infeed motion for depositing ware upon the leer conveyor, which cycle ends with the parts in position to deposit further ware upon the leer conveyor, but which parts, having come to a stop in such position, will be set in motion to operate through another cycle only when fresh ware has been brought up in position to be transferred to the leer conveyor, the construction being such, however, that, if desired, the mechanism may be kept in continuous operation, being actuated continuously through a series of cycles.

A further object of the invention is the provision of such mechanism in which the infeed or pusher member, having completed its infeed motion, travels through a path leading upwardly and over the tops of any fresh ware that may be in the course of being brought up into position to be placed upon the leer con-

veyor during the next cycle of operation of the pusher member.

A further object of the invention is the provision of such a loader so constructed that it may be placed in juxtaposition to and used with different kinds of annealing leers of the conveyor type.

A still further object is the provision of a loading mechanism that can be set in motion by the arrival of very small, lightweight glass articles, such for example as very small bottles, in position with respect to the leer conveyor to be placed thereon by the loading mechanism.

Other objects and advantages of the invention, not herein specifically referred to, will appear from the following description taken in connection with the accompanying drawings which illustrate by way of example a preferred embodiment of the invention, and in which:

Figure 1 is a top plan view of a leer loader constructed in accordance with the invention;

Figures 2 and 2A are complementary views showing the loader of Fig. 1 in end elevation, with certain parts in section;

Figure 3 is a side elevation on a slightly enlarged scale, looking at Fig. 2A from the right, and showing the upper portion of the mechanism;

Figure 3A is a view similar to Fig. 3 and complementary thereto, showing in elevation the lower portion of the same side of the loader;

Figure 4 is an enlarged vertical sectional view showing one form of mounting support for the loader;

Figure 5 is a vertical sectional view on a somewhat enlarged scale and taken on the line 5—5 of Fig. 2A;

Figure 6 is an enlarged elevational fragmentary view showing part of the mechanism of Fig. 2A;

Figure 7 is a diagrammatic view showing a preferred form of circuit and mechanism associated therewith for controlling the operation of the loader.

Referring in detail to the drawings, the invention as here illustrated includes a frame comprising four corner uprights 11, connected by upper and lower side and end members 13.

The loader is shown, by way of illustration, as being placed adjacent and in operative relation to the entrance end of a leer, only the forward part of the leer being shown, the leer itself forming no part of the present invention but being described and claimed in my copending application Serial No. 580,080, now Patent No. 1,919,923. 110

The leer has a travelling conveyor passing through it, which is herein shown as being in the form of a chain link conveyor belt 15 passing over an upper guide roller 17, the horizontal ware-carrying portion of which, in operation, moves away from the observer, looking at Figures 2 and 2A. Closely adjacent the entering portion of the horizontal conveyor belt of the leer, and preferably extending the full width of said conveyor, is one edge 5 of a stationary platform 19 along whose opposite edge moves a constantly travelling, relatively narrow, endless conveyor 23, travelling horizontally in a direction at right angles to the direction of travel of the leer conveyor belt 15. The conveyor 10 or 23 has bottles or other ware to be annealed delivered to it by any means such, for example, as the constantly rotating turntable 25 and its fixed guide arm 27.

The invention includes mechanism for shifting 20 a row of bottles, in alignment and travelling on conveyor 23, from said conveyor, and at right angles to its direction of travel, across the stationary platform 19 and upon the leer conveyor 15, which carries the ware, hereinafter and by way 25 of illustration referred to as bottles, through the leer for annealing.

As herein shown, the bottles are transferred to the leer conveyor 15 from their aligned position on conveyor 23 by means of a pusher bar 29 30 adapted to travel from a relatively low position near conveyor 23 horizontally to the left, as viewed in Figure 5; thence, when the bottles have been deposited on the leer conveyor, travelling upwardly and rearwardly high enough for the 35 pusher bar to clear, in its backward travel, the tops of fresh ware being brought along by conveyor 23, as shown in full position in Figure 5; thence travelling downwardly to right hand dotted line position of Figure 5, until the arrival of 40 a bottle on conveyor 23 in predetermined position with respect to the leer conveyor causes the pusher bar actuator mechanism to be set in motion, whereupon the pusher bar starts again on the initial horizontal travel of its circuit, moving from 45 the right hand dotted line position of Fig. 5 to the left hand dotted line position in said figure.

As illustrated in the drawings, the pusher bar 29 is carried by the lower end of a pair of vertically extending carrier rods 33, each of which is 50 vertically movable in a guide 35. These guides are mounted on a horizontal support 37 connecting the two substantially parallel sides 39 of a horizontally reciprocable carriage formed by said sides and their horizontal connecting support 37. 55 This carriage may be provided with wheels, as shown in the drawings, the right hand wheels 41 being flanged or beveled to travel in suitably shaped guide tracks 43, and the left hand wheels 45 being flat and travelling upon flat tracks 47, 60 the construction described allowing the flat trimmed wheels 45 to shift transversely of their supporting tracks with expansion and contraction of the carriage, and particularly the connecting support 37, with changes of temperature, 65 while, at the same time, insuring accurately guided travel of the carriage in operation.

Means are provided for giving the pusher bar carriage a horizontally reciprocating motion, such means cooperating with mechanism for raising and lowering the pusher bar rods 33, so that lifting 70 of the pusher bar is completed before the pusher bar reaches its upper rear position due to the backstroke of the carriage, and so that the carriage remains stationary during the travel of 75 the pusher bar from its upper rear position to its

lower rear position, or preparatory position, shown in the right hand dotted lines of Fig. 5.

As herein illustrated, links 51 connect the pusher bar carriage with the lower ends 53 of a pair of rocking cam frames 55, each of whose upper ends 57 is pivoted as at 59 to a stationary mounting member 61 fixed to the main frame of the mechanism. The upper end 57 of each frame 55 is rigidly connected to the lower end of the frame by cam actuated side bars 63 and 65. Each cam frame is adapted to rock about its pivot 59 from the full line position of Fig. 5 to the dotted line position of said figure, and thus, by means of links 51, the pusher bar carriage is shifted back and forth in its horizontal path of travel. 80 85 90

For the purpose of oscillating each rocker frame 55, in predetermined timed relation to means hereinafter described for raising and lowering the pusher bar, a horizontal cam shaft 71, mounted in suitable fixed bearings 73 carried 95 by the main frame, has fixed thereon a cam 75 located within the carriage oscillator frame 55 and adapted alternately to act against the inner face of each of the oscillator frame side bars 63. The cam shaft 71 rotates in a clockwise direction, 100 as viewed in Fig. 5.

Cooperating in timed relation with the oscillator mechanism just described, the invention provides means for raising and lowering the pusher bar 29 by means of its supporting rods 33. As 105 herein illustrated (Figs. 2, 2A and 5), the two pusher bar supporting rods 33 have their upper ends connected by a cross bar 77, which is adjustably secured to the upper threaded ends of said rods by securing nuts 79. The cross bar 77 110 has rotatably mounted on it a pair of spaced grooved rollers 81 and may also carry a certain part of the control mechanism hereinafter described.

The pusher bar, its supporting rods 33, and 115 cross bar 77 form a relatively rigid unit supported by a pair of raising and lowering arms 83, each of which is pivoted, as at 85 to a stationary portion 87 of the main frame, and each of which bears against the underside of one of the grooved 120 rollers 81, supporting the pusher bar unit. As herein shown, the raising and lowering arms 83 do not travel forwardly and rearwardly with the carriage but rock up and down in a vertical plane about their horizontal fixed pivots 85 to control 125 the vertical position of the pusher bar.

Carried by the cam shaft 71, for each raising and lowering arm 83, is a cam 91 which bears upon the lower face portion of its raising and lowering arm, these cams 91, by their clockwise rotation 130 (as viewed in Fig. 5) oscillating the raising and lowering arms in a vertical plane about their fixed pivots. Fig. 5 shows in full lines the raising and lowering arms in their uppermost position, and in dotted lines in intermediate and 135 lowermost positions. The cams 75 and 91 are so arranged that the pusher bar moves rectilinearly from its upper rear to its lower rear position and rectilinearly horizontally during its 140 advance or bottle-pushing stroke. At the end of its advance stroke, it starts upwardly, due to the action of cams 91 on raising and lowering arms 83, but before reaching the limit of its upward movement, cams 75, acting upon oscillator frames 55, begin the withdrawing or return movement 145 of the pusher bar carriage, so that the pusher bar begins rearward movement in its upper path before reaching its greatest height above the conveyor 23. It should, however, and in the present example of the invention does, reach its upper- 150 155

most limit before its rearward stroke is completed, thereby insuring all available clearance height of the pusher bar over bottles being brought up by conveyer 23.

5 In accordance with the invention, the pusher bar, on completion of its cycle, comes to rest in its lower right hand dotted line position of Fig. 5, and will advance in bottle-pushing movement, starting another cycle, only if a bottle on conveyor 10 23 has arrived upon said conveyor in a predetermined position. By arriving in this position the bottle sets in motion the actuating mechanism, starting another cycle, only if a bottle on conveyor 15 23 has arrived upon said conveyor in a predetermined position. A further cycle of movement of the pusher bar is commenced upon the arrival of another bottle in said predetermined position. Accordingly, the cam shaft 71 does not rotate continuously, but 20 only during operation of the pusher bar through its cycle.

The actuating mechanism for cam shaft 71 includes a motor 95 which is in continuous operation during the time bottles are being fed into the leer. This motor, by a belt 97, drives a pulley 25 99 which, through a Reeves transmission 101, drives a shaft 103 carrying a sprocket wheel connected by a chain 105 with a sprocket wheel 107, which drives a continuously rotating sleeve 109, 30 within which is located a rotatable shaft 111 mounted in bearings 113, the sleeve 109 being rotatable in fixed bearings 115. Through the mechanism about to be described, the shaft 111 remains stationary or is connected to rotate with the sleeve 109, depending upon whether a bottle is 35 present to start another pusher bar cycle, that is, has arrived in predetermined position to be transferred by the pushed bar 29 from conveyor 23 across the platform and onto the leer conveyor 15.

40 Referring particularly to Figs. 1 and 3, one end of the sleeve 109 is formed as a clutch face with which may be engaged a cooperating clutch member 117 feathered on shaft 111 and moved into and out of clutching position by a yoke 119 pivoted at 121 to a stationary support 123, the upper end 45 125 of the yoke being controlled by the electromagnet 127, the arrangement being such that, with current flowing in the magnet coil, the shaft 50 111 rotates with continuously rotating sleeve 109 and, when the magnet coil circuit is broken, the clutch member 117 is disengaged from sleeve 109 so that shaft 111 comes to a stop. Current will 55 flow in the magnet coil or not depending upon the action of the control mechanism hereinafter described.

Shaft 111 carries a sprocket wheel connected by a chain with a sprocket wheel 133 on horizontal shaft 135 and driving, through a worm 137, a 60 worm wheel 139 fast on cam shaft 71, the worm and worm wheel being enclosed in a suitable housing 141.

65 Continuously rotating sleeve 109 has fixed thereon a sprocket 143 connected by a chain 145 to a cooperating sprocket 147 fast on an intermediate shaft 149 rotatably mounted in fixed bearings 151 and also having fixed thereon a sprocket wheel by means of which, through chain 153 (Figs. 3 and 3A), it drives a sprocket wheel 155 70 on a horizontal shaft 157 carrying a gear 159 in mesh with a cooperating gear 161 on a horizontal conveyor drive shaft 163, which continuously rotates the driving drum 165 of conveyor 23. The turntable 25 may be driven from shaft 163 by a 75 sprocket wheel 167 on said shaft connected by a

chain 169 to a cooperating sprocket on a short horizontal shaft 171 carrying a bevel gear 173 in mesh with a cooperating bevel gear 175 fast on the vertical turntable shaft 177.

80 Referring now to Figs. 2A and 3A, the invention includes means which detects the presence of a bottle and thus starts the pusher bar cycle. In practice, as here illustrated, this bottle is the lead bottle of a series whose length is substantially the same as the width of the leer conveyor. When the lead bottle of the oncoming series on conveyor 23 has advanced far enough so that it will occupy a position near the far side edge of the leer conveyor when placed thereon, such lead bottle sets in motion the pusher bar, starting it 85 on its cycle and causing the placing of the lead bottle and its series, up to the effective length of the pusher bar, upon the leer conveyor belt.

90 In the present embodiment of the invention this means includes a bottle strike 181 which, in the present instance, is a lightweight transverse bar carried at the end of a rod 183 supported on an idle roller 185 mounted on the main frame of the mechanism. At its other end, the rod 183 is pivoted to the lower end of a downwardly extending lever arm 187 carried by and in fixed relation with a tilting mercury switch support 189, which may be oscillated vertically about its fixed horizontal pivot 191 to slope downwardly to the right, as viewed in Figs. 2A and 7, or downwardly to the 100 left, as viewed in said figures. The parts are so arranged and so balanced that an extremely small force, such as that exerted by a very small bottle carried on conveyor 23, will move the rod 183 to the right, as viewed in Figs. 2A and 7, far enough 105 to reverse the direction of slope of mercury switch support 189. For the purpose of effecting a nice balance of the parts, so that the bottle strike may be easily moved and yet will normally occupy the position of Fig. 2A, a projection 193 on support 115 189 may carry adjustably thereon a small regulating weight 195. The support 189 has fixed thereon a mercury switch A (Figs. 2A and 7). Mercury switch A, when actuated, momentarily 120 closes a circuit hereinafter described, maintaining it closed only until the bottle which tilted the switch A is moved off conveyor 23 by the pusher bar, whereupon mercury switch A returns to the 125 position of Fig. 2A by gravity, in readiness to be operated by the arrival of the lead bottle of the next oncoming series. This momentary actuation of mercury switch A, however, closes a holding circuit which, in turn, holds closed the circuit including the coil of magnetic switch 127, thereby 130 clutching shaft 111 to continuously rotating sleeve 109 and starting and continuing the push bar upon its cycle, as hereinafter more fully described, until the cycle is completed. The circuit holding closed the switch causing current to flow in the 135 electromagnet 127 is broken at the proper time 140 to bring the pusher bar to a stop in its lower right hand dotted line position of Fig. 5 and, as here shown, for this purpose, cross bar 77 has fixed to it by a yoke clamp 197 a vertically extending push pin 199 (Figs. 2A and 6). Lying in the 145 path of the push pin 199 as it travels rectilinearly downwardly during movement of the push bar from its upper full line position of Fig. 5 to its lower right hand dotted line position of that figure, are, successively and one at a time, a series of radial teeth or projections 201 on a toothed wheel 203, rotatable in a vertical plane on a horizontal shaft 205. In the present instance, the number of 150 projections or teeth 201 is shown as 10. Fixed on shaft 205 and rotatable with it and toothed

wheel 203 is a cam wheel 207, having equally spaced raised cam portions 211, and between each two adjacent raised portions a lower cam portion 209, the sum of the raised cam portions 211 and 5 lower cam portions 209 being ten, there being five of each, alternately arranged, and their sum being equal to the number of projecting teeth 201 on toothed wheel 203.

A second mercury switch B is carried on a lever 10 arm 213, rockable in a vertical plane about a horizontal pivot 215, and carrying in fixed relation therewith a downwardly projecting arm 217, upon the lower end of which is mounted a small roller 219 riding on the peripheral surface of the cam 15 wheel 207, and occupying alternately a position upon a raised cam portion 211, then on the next succeeding lower cam portion 209, then upon the next raised portion 211, etc., as the cam wheel 207 is given intermittent rotational movement in a 20 clockwise direction, as viewed in Fig. 6. A movement of toothed wheel 203, due to one down stroke of push pin 199, is just sufficient to cause the roller 219 to occupy a position on one cam portion, for example, a raised cam portion 211, then to 25 occupy a position on the lower cam portion 209 upon the next succeeding down stroke of the push pin, then upon the next raised cam portion, etc.

As a result, the lever arm 213 carrying mercury switch B occupies alternately two positions, 30 one in which mercury switch B slopes downwardly to the left, as viewed in Fig. 6, and the other a position in which said switch slopes downwardly to the right, as viewed in Fig. 6.

Referring now particularly to Fig. 7, the mercury switch A is shown in the position it occupies before it is actuated by the leading bottle of an oncoming series. When a bottle moves the rod 183 to the right, as viewed in Fig. 7, over its supporting roller, the mercury switch A is tilted about its pivot in a counter-clockwise direction, so that its terminals A1 and A2 are bridged by the mercury. Current then flows from supply line L2, through conductors C1, C2, switch terminals A1, 40 A2, conductor C3, through terminals B2, B1, of mercury switch B, conductor C4, the coil of electromagnet switch S, to supply line L1. The three-pole switch is thereby closed, so that current from the main line flows from L2, through middle arm of switch S, through conductor C7, coil of electromagnet 127, through conductor C6, and left arm of switch S to supply line L1. The clutch part 117 is thereby engaged with sleeve 109 and shaft 111 is rotated to operate the cam shaft 71 and start the pusher bar 29 on the way through its cycle.

55 When the lead bottle has been pushed by the pusher bar 29 away from the strike 181 of rod 183, the mercury switch A, by gravity, resumes the position of Fig. 7, so that the circuit through its terminals A1 and A2 is broken. However, the switch S being closed, current from line L2 now flows through the right hand or holding circuit arm of the switch, through conductor C5, switch S2 (which is assumed to have been manually closed in preparation for commencing a series of feeding operations), conductor C3, switch terminals B2 and B1 of mercury switch B, through conductor C4 and coil of switch S to supply line L1. This holding circuit keeps the switch S closed, so that current continues to flow in the 60 coil of electromagnet 127, with the result that shaft 111 and cam shaft 71 continue their rotation through one cycle. When the cam wheel 207 is actuated (by the push pin 199, as hereinbefore described), at the close of the pusher bar cycle, 75 the roller 219 of the supporting lever for switch B

drops from the raised cam portion 211 down into the lower cam portion 209 of the cam wheel, so that the switch B is tilted in a direction opposite to that shown in Fig. 7. This opens the circuit through switch terminals B1 and B2 momentarily and then, when the mercury reaches the right hand end of the tube, closes the switch terminals B3 and B4. The momentary breaking of the circuit through switch terminals B1 and B2 breaks the circuit through the coil of switch S, so that the switch is opened by its tension spring 126. Current therefore ceases to flow in the coil of electromagnet 127 so that clutch member 117 is disengaged from sleeve 109, and shaft 111 ceases to drive cam shaft 71, with the result that the pusher bar comes to a stop at the bottom of its down stroke, in starting position, ready for the lead bottle of the next series of oncoming bottles to cause rod 183 to move to the right, as viewed in Fig. 7. When it does so, switch A closes as before described and current from line L2 flows through conductors C1, C2, momentarily through switch terminals A1 and A2, conductor C3, switch terminals B3, B4, conductor C4, and then through the coil of switch S as before, closing the three-pole switch S and causing current to flow in the coil of electromagnet 127 and thus causing cam shaft 71 to operate the pusher bar through another cycle. When the lead bottle has ceased to urge the rod 183 towards the right, as viewed in Fig. 7, switch A opens again by gravity, but the switch S having been closed, current flows from line L2 through the right hand closed arm of switch S, conductor C5, closed switch S2, conductor C3, switch terminals B3, B4, conductor C4, and coil of switch S, thereby holding the switch S in closed position, so that the pusher bar continues its cycle until it is completed again, whereupon cam wheel 207 is moved as before described to reverse the direction of tilt of mercury switch B and to turn it to the position of Fig. 7. The momentary breaking of the circuit through switch terminals B3 and B4 allows switch S to open by means of its tension spring, so that electromagnet 127 no longer holds shaft 111 in driving engagement with sleeve 109. Upon the arrival of the mercury in switch B in position to close switch terminals B1 and B2, the parts are in position to operate through another cycle as soon as another oncoming lead bottle of a series momentarily closes the circuit through switch terminals A1 and A2, whereupon the pusher bar goes through another cycle as already described.

What is claimed is:

1. A leer loader including a leer feeder member, feeder member moving means for moving said feeder member through a predetermined path which includes an infeed stroke and a return stroke, means associated with said feeder member moving means for elevating said feeder member on a return stroke, driving means for said feeder member moving means, an electromagnetic clutch for bringing said feeder member moving means into and out of driven relation to said driving means, a circuit for said clutch, and a ware actuated switch for controlling said circuit.

2. A leer loader including a leer feeder member, feeder member moving means for moving said feeder member through a predetermined path including an infeed stroke and a return stroke, driving means for said feeder member moving means, an electromagnetic clutch for bringing said feeder member moving means into and out of driven relation to said driving means, a circuit for said electromagnetic clutch, a ware actuated

switch in said circuit for operating said clutch means into and out of driven relation to said driving means, a clutch circuit including a clutch control switch, a holding circuit for said clutch control switch, a starting switch in the holding circuit, a ware actuated strike member for moving the starting switch and thereby moving the clutch control switch to bring the feeder member moving means into and hold it in driven relation to said driving means, and a stopping switch in the holding circuit, said feeder member on its return stroke first opening the stopping switch in the holding circuit and thereby bringing the feeder member moving means out of driven relation to said driving means and then closing said stopping switch in preparation for another closing of the holding circuit by ware actuation of the strike member.

3. A leer loader including a leer feeder member, means for moving said feeder member through a predetermined path including an infeed stroke and a return stroke, driving means for said feeder member moving means, an electromagnetic clutch for bringing said feeder member moving means into and out of driven relation to said driving means, a clutch circuit, a clutch control switch therein, and a holding circuit associated with said clutch control switch and including a ware actuated starting switch for closing the holding circuit and thereby said clutch control switch, said holding circuit including also a stopping switch controlled by the return stroke of the feeder member for breaking the holding circuit and thereby opening the clutch control switch.

4. A leer loader including a leer feeder member, means for moving said feeder member through a predetermined path including an infeed stroke and a return stroke, driving means for the feeder member moving means, an electrically actuated clutch for bringing said feeder member moving means into and out of driven relation to said driving means, a clutch circuit including a clutch control switch, a holding circuit for said clutch control switch, a starting switch in the holding circuit and a ware actuated strike member for moving the starting switch and thereby moving the clutch control switch to bring the feeder member moving means into driven relation to said driving means.

5. A leer loader including a leer feeder member, means for moving said feeder member through a predetermined path including an infeed stroke and a return stroke, driving means for the feeder member moving means, an electrically actuated clutch for bringing said feeder member moving means into and out of driven relation to said driving means, a clutch circuit including a clutch control switch, a holding circuit for said clutch control switch, a starting switch in the holding circuit, a ware actuated strike member for moving the starting switch and thereby moving the clutch control switch to bring the feeder member moving means into driven relation to said driving means, and a stopping switch in said holding circuit actuated by the return stroke of the feeder member to break the holding circuit and thereby bring the feeder member moving means out of driven relation to said driving means.

6. A leer loader including a leer feeder member, means for moving said feeder member through a predetermined path including an infeed stroke and a return stroke, driving means for the feeder member moving means, an electrically actuated clutch for bringing said feeder member moving

means into and out of driven relation to said driving means, a clutch circuit including a clutch control switch, a holding circuit for said clutch control switch, a starting switch in the holding circuit, a ware actuated strike member for moving the starting switch and thereby moving the clutch control switch to bring the feeder member moving means into and hold it in driven relation to said driving means, and a stopping switch in the holding circuit, said feeder member on its return stroke first opening the stopping switch in the holding circuit and thereby bringing the feeder member moving means out of driven relation to said driving means and then closing said stopping switch in preparation for another closing of the holding circuit by ware actuation of the strike member.

7. A leer loader including a bringing up conveyor, a leer feeder member associated therewith, means for moving said feeder member through a ware feeding path which includes a substantially rectilinear infeed stroke close to said bringing up conveyor and a higher ware-clearing return stroke above said conveyor, means controlled by the movement of the feeder member for bringing the feeder member to a stop at the end of its return stroke, and mechanism controlled by ware on said conveyor for setting in action the feeder member moving means.

8. A leer loader for placing glassware upon a leer conveyor and including a platform for contiguous relation to such leer conveyor, a continuously operable bringing up conveyor associated with said platform, a leer feeder member for transferring ware from the bringing up conveyor and across the platform onto the leer conveyor, means for moving the feeder member through a ware feeding path which includes a substantially rectilinear infeed stroke in the direction of travel of the leer conveyor and across the line of travel of the bringing up conveyor and a higher ware clearing return stroke above the bringing up conveyor, means controlled by movement of the feeder member for bringing it to a stop on completion of its return stroke, and mechanism controlled by ware on the bringing up conveyor for setting in action the feeder member moving means.

9. A leer loader including a bringing up conveyor, a leer feeder member associated therewith, supporting means therefor, means for moving said feeder member forwardly on an infeed stroke and then rearwardly on a return stroke, mechanism for lowering the supporting means for the infeed stroke of the feeder member and raising the supporting means on the return stroke of the feeder member, actuating mechanism for the supporting means and feeder member moving means, a substantially horizontally movable counterbalanced ware strike movable by ware on the bringing up conveyor for setting in motion said actuating mechanism, and a roller support therefor intermediate the ends of said strike.

LOUIS BEON. 140
